UNITED STATES PATENT OFFICE.

WESTERN UNDERWOOD, OF LOS ANGELES, CALIFORNIA, ASSIGNOR OF ONE-HALF TO H. H. WALKER, OF LOS ANGELES, CALIFORNIA.

DESIGN FOR A CANOPY FOR LAMPS.

Application filed July 16, 1923. Serial No. 6,782. Term of patent 7 years.

To all whom it may concern:

Be it known that I, WESTERN UNDERWOOD, a citizen of the United States, residing at Los Angeles, in the county of Los Angeles and State of California, have invented new, original, and ornamental Design for Canopy for Lamps, of which the following is a specification, reference being had to the accompanying drawing, forming part thereof.

The figure is a perspective view of the canopy.

I claim:

The ornamental design for a canopy for lamps, as shown.

WESTERN UNDERWOOD.
